G. CLAUSING

GOLF TEE

Filed March 19, 1927

INVENTOR
George Clauising
BY *Toulmin Toulmin*,
ATTORNEY

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

GOLF TEE.

Application filed March 19, 1927. Serial No. 176,810.

My invention relates to golf tees.

It is the object of my invention to provide a golf tee which will not turn in the ground and will maintain itself in a firm steady position resisting the torsional effect of the impact of the ball, as it is seldom that the club hits the ball squarely, and, as a result torsional strains are set up which serve to rotate the tee loosening it from the ground and ejecting it.

It is a further object of my invention to provide in this combination a golf ball supporting head in which the points of support or lines of support will be adequate for positioning the ball, but will be of the minimum area and will be so arranged that the body of the tee will be sufficiently removed from the points of support so that the ball will not come in contact with the body.

20 Referring to the drawings:

Figure 1 is a side elevation partially in section of a tee having an angular ground engaging shaft and a four-point engaging head, the surface of the head being flat;

25 Figure 2 is a top plan view of Figure 1;

Figure 3 is a bottom plan view of Figure 1.

Figure 4 is a side elevation partially in section of a slightly modified form;

30 Figure 5 is a top plan view thereof illustrating the broken circle type of golf ball engaging edge;

Figure 6 is a bottom plan view of Figure 4;

35 Figure 7 is a side elevation of a triangular form of tee;

Figure 8 is a top plan view thereof;

Figure 9 is a bottom plan view thereof.

Referring to the drawings in detail, 1 is a body which may be either square or triangular or rectangular.

This body is mounted upon, preferably as an integral part thereof, a ground engaging portion consisting of a pyramid having flat surfaces 2 and sharp downwardly tapering edges 3 which terminate in a point 4.

This pyramid may either have three sides

or four sides or any number of sides. The desired object is to provide flat engaging surfaces to provide relatively broad bearing surfaces in engagement with the ground in combination with sharp edges between the surfaces to provide the maximum of resistance to the rotation of the golf tee coupled with ready penetration of it into the ground.

The body itself is provided with a flat upper surface 5 or an arcuate surface 6, the result in both cases being the same that the upper surface of the body is not brought in contact with the ball.

The body provides on its corners upstanding ball engaging portions 7 which may either engage the ball on the points 8 or the semi-circular surfaces 9.

In Figures 7, 8 and 9, the structure is triangular, while, in the other figures, the structure is rectangular.

It will be understood that I desire to comprehend within my invention such modifications as may be necessary to adapt it to varying conditions and uses.

Having thus fully described my invention, what I claim as new and desire to secure by Letters Patent, is:

1. In a golf tee, a head having a semi-circular depressed upper surface, and a plurality of semi-circular upstanding golf ball engaging edges, said depressed surface and golf ball engaging edges being laid out on the surface of the semi-circular head, and a depending ground engaging member for supporting the head.

2. In a golf tee, a head having a semi-circular depressed upper surface, and a plurality of semi-circular upstanding golf ball engaging edges, said depressed surface and golf ball engaging edges being laid out on the surface of the semi-circular head, and a depending ground engaging member for supporting the head, said ground engaging member having flat sides tapering to a point.

In testimony whereof, I affix my signature.

GEORGE CLAUSING.
